FUSED PLUG AND MULTIPLE TAP FOR
ELECTRICAL CORDS

Matthew E. Gerlat, Milwaukee, Wis.

Application November 22, 1950, Serial No. 197,061

13 Claims. (Cl. 200—115.5)

1

This invention relates to improvements in plugs for or for use in connection with electrical cords and extension cords which are to be connected to the usual types of electrical receptacles, and particularly to plugs embodying in their construction fuses for the several conductors of the cords.

The construction of fused plugs is subject to quite contradictory requirements imposed by the uses for and the users of such cords, by conditions to be met to keep the costs of the plug as low as possible, and by safety requirements imposed by state statutes and municipal ordinances, by fire insurance underwriters and by other agencies concerned with the safety of electrical appliances.

It is therefore one object of the present invention to provide a fused plug for an electrical cord, which requires a minimum of parts and a minimum of time for assembly of the plug with the cord.

Another object of the invention is to provide a fused plug for electrical cords, in which "strain-relief" on the cord, insulation between conductive parts, and other safety requirements are met in a simple manner.

A further object of the invention is to provide a fused electrical plug in which removal and replacement of the fuse or fuses is easily and quickly performed without tools of any kind.

Another object of the invention is to provide a fused plug for electrical cords, in which springs or spring-action members severally press the fuses axially against the prongs to maintain adequate electrical contact between the fuses and the prongs, and in which the springs also provide axial pressure for ejecting the fuses from the plug body upon disengagement of the prongs from the plug body.

Another object of the invention is to provide an electrical cord plug with fuses in which the body of the plug provides the sole means for locating the fuses and for holding the fuses in the desired relation to the prongs and to the cord ends, with which the fuses are to remain in electrical conductive relation.

Another object of the invention is to provide a fused plug for electrical cords in which the cord ends are simply and quickly attached to the conductive elements of the plug, whether the cord and plug are assembled as a factory operation or by individual users of the plug.

And a further object of the invention is to provide a multiple outlet electric plug or tap for insertion in an electrical receptacle and for con-

2

nnection thereto of a plurality of electrical cords, and in which a single pair of fuses within the body of the tap conducts the electric current to all of the electrical cords attached to the tap.

In the present construction, the plug or tap body is formed of two generally similar parts of a dielectric and preferably somewhat resilient material. The body parts are so designed as to provide for easy insertion and removal of the plug or tap in an electrical receptacle and to resist damage to the plug or tap during use. When the plug is designed for use with separate conductors, entry of the electrical cord conductors into the plug is by way of considerably separated apertures, and separate cavities are formed in one body part (female) to receive projections from the other body part (male) for sharply crimping or otherwise holding the conductors to resist tension on or provide "strain-relief" for the conductors.

Generally similar female and male body parts are likewise utilized where the conductors are combined into a single cord, which enters the plug through a single aperture. The "strain-relief" is then provided either (or both) by attachment of the cord conductors severally to the contact members held under spring pressure within a chamber formed therefor in the plug body, by compressing the cord as a whole between toothed portions of the plug body parts which may be resilient, by clamping of the separate conductors in a sinuous path inside the plug body, or by a member performing the functions both of an electrical contact and a pressure spring seated within the plug body.

The plug body and tap parts have a substantially plane surface for contact when the plug is assembled but such surfaces have various complementary projections and depressions for locating the parts relative to each other, and for strengthening the parts.

Each of the body parts (other than the "strain-relief" portions thereof) is formed with cavities which are identical except in size in the various modifications of the plug and tap. As to the plug, the cavities include, for each conductor, a first chamber for receiving an end of the conductor and a spring combined with a contact member or a separate contact member, and to receive a known type of fuse for conductive contact with the conductor. A second chamber is joined with the first chamber to form a portion of means for locking the fuses and readily releasable plug prongs within the plug or tap body, and a passage connects such second chamber with the end of

the plug or tap for entry into the body of the fuses and of a portion of the prongs.

The means for locking the fuse and prong into the plug or tap body includes notches formed in the wall of the second chamber to receive lugs extending from sockets formed on one end of each prong, the sockets severally receiving one end of a fuse. Grooves are provided in the entry passageway wall for inserting the prongs into the second chamber and such chamber is of an axial length not greatly in excess of that required for rotation of the prong lugs therein.

Objects and advantages other than those above set forth, will be apparent from the following description when read in relation to the accompanying drawings in which:

Fig. 40 is a perspective view of one of the spring-contact members utilized in the tap.

Referring particularly to Figs. 1 to 8 of the drawings by reference numerals, the numeral 25 designates a female body part and numeral 26 designates a male body part, the two body parts being complementary when assembled. The body part 25 is formed with a pair of similar cavities 27 which are severally adapted to receive projections 28 from the body part 26. It will be noted that the projections 28 are severally considerably smaller in thickness than the width of the cavities 27 and severally have a notch 29 therein, the projections severally extending into the cavities in spaced relation from the ends of the cavities. Similar grooves 30 and 31 extend severally from the cavities 27 and from the sides of the projections 28 to one of the ends of the plug body parts 25 and 26.

Pairs of identical cavities 36, 37 are formed in both of the plug body parts 25 and 26. When the plug is assembled, the cavities 36, 37 coact to provide first chambers connected at one end by grooves 38 and 39 respectively to the cavities 27 and the sides of the projections 28. The other ends of the first chambers 36, 37 are connected with another pair of cavities 40 and 41 to form second chambers which are larger in diameter but of less length than first chambers 36, 37.

Notches 42 are formed in the wall of the second

chambers and on a diameter thereof. The second chambers 40, 41 are connected by grooves 43 and 44 coating in assembled relation of the plug body for forming passages to one end of the plug body, and each such passageway has a pair of rectangular grooves 45 in the wall thereof, which are diametrically opposed when the plug body is assembled.

Each of the body parts is formed with projections 46 from the body parts 25, 26 and with matching notches 47 in such body parts, the projections and notches extending from and into the walls forming the sides of the grooves 43, 44. The projections and notches aid in locating the body parts relative to each other and interrupt the otherwise substantially planar joint between the body parts. The pressure exerted at such joint by the prongs thus acts on considerable masses of the body parts rather than only on adjacent edges of the body parts, which minimizes breakage due to such pressure.

Each of the first chambers 36, 37 is adapted to receive a spring 50 abutting against one end of such chamber and abutting at the other end on a contact member 51 to which the spring may be attached if desired. In the first modification of the invention, the spring is a helical compression spring made of any desired material as such spring is not required to conduct electrical current, but the member 51 is of good conductive material. The conductors 52 of the extension cord are severally attached to the contact members 51 as by soldering.

Prongs (see Figs. 9 and 10) for entering an electrical receptacle, are formed from a strip of metal which is preferably somewhat resilient and with the ends thereof severally formed to provide similar semi-circular portions 57, 58 with rectangular lugs 59 formed from each such portion. The prong strip is then folded to provide somewhat bowed adjacent portions 60, 61 and to bring the end portions 57, 58 adjacent in the form of a socket with the lugs 59 in diametrically opposed relation. Each socket 57, 58 is of a diameter to receive the end of a fuse 62 even when the portions forming each prong are pressed together to enter passages 43, 44. The fuse is a type now in general use and requires no particular description.

The spring described above may also be made as shown in Figs. 11 and 13 inclusive in which the spring is Phosphor bronze with a main portion 65 formed as a helix and with the ends of the springs spiraled inwardly in the end turn of the spring to provide substantial circular loops 66. Such loops are of a size to receive the end of a conductor 67 of the electrical cord, for joining the conductor end to the spring as by solder 68. If the conductor-spring connection is to be factory made, the above construction is used. However, if the conductor is to be attached to the spring by individuals to whom solder and soldering means are not readily available, a contact member 69 is applied to the end of the spring and is joined thereto as by solder. The contact member is then formed with a threaded aperture for receiving a screw 70 by which the conductor 67 may be readily attached to the spring in conductive relation.

The construction shown in Figs. 1 to 11 is particularly adapted for electrical cords where the conductors are separate or easily separable and of small size and are only individually insulated so that a V-bend may be made in such conductors without imposing any considerable stresses on the plug body parts, the V-bend pro-

viding more than the amount of "strain-relief" usually required by safety regulations. Such cords are usually intended for relatively low currents and the dimensions of the plug parts and the cavities are therefore such as to receive only a fuse of low current carrying capacity. However, when the cords are to be capable of carrying higher currents, the individually insulated conductors are usually combined into a single cord with additional insulation about the joined conductors, such cords then becoming too heavy for the crimping shown in Figs. 5 and 6.

The plug body portions to be used for carrying larger currents, are made as shown in Figs. 15 to 21 inclusive. In Figs. 15 to 18 inclusive the body parts are again a female body portion 75 and a male body portion 76, and the first chambers therein are connected by a single semi-circular groove 77 which is connected with a single groove 78 extending to the end of the plug body. In one modification of the plugs, the female body part 75 is formed with a cavity 79 with angular sides and intermediate the ends of the groove 78. Projections 80 are formed on body 20 part 76 to provide a seat for the cord. The material of which the body parts are made, is sufficiently flexible and resilient to allow deflection toward each other of projections 80 upon their entry into cavity 79 in assembling the plug. The 25 projections have non-adjacent sides at an angle which is different from the angle of the sides of cavity 79, and have vertical adjacent sides. Hence, a cord combined of the separately insulated conductors 81, 82 and either with or without additional insulation, may be compressed between the projections. The vertical sides of the projection 80 are formed with non-matching vertical serrations 83 which imbed themselves into the cord when the plug is assembled. If the cord conductor is made of relatively light stranded wires as usual in heavy current extension cords, both the insulation and the conductors of the cord are compressed and deformed to grip the cord tightly in the plug.

Conic or pyramidal projections 84 extend from the wall of the groove 77 in offset or staggered relation so that the separate cord conductors must take a sinuous form when placed into such grooves. Compression of the conductors 81, 82 in the groove 77 about the projections 80 and imbedding of the serrations 83 in such conductors and their insulation provides resistance to movement of the separate conductors and avoids the transmission of tension on the cord beyond such projections and toward the conductor-spring joints.

The grooves 78 in the plug body parts may also be made with ribs 88 extending diagonally across grooves 78, as shown in Figs. 19 and 20, the ribs being of such shape and size as to deform the insulation about the individual conductors of the cord and the conductors themselves, if the conductors are multiple thin strands. The deformation of both the insulation and the wire portion of stranded conductors is sufficient to take up any tension on the cord even when such tension is applied in jerks. In any event such deformations have resisted cord movement at continuous tension of more than thirty pounds and have resisted substantially the same pull applied in jerks, each of which forces are more than sufficient to pull the plug free from any electrical receptacle on the market.

In assembly, a spring is placed about a conductor and a contact member is attached to the end

of the conductor as shown in Figs. 1 to 11 or the conductor is directly attached to a contact member as in Figs. 11 to 14. Such assembly is placed in the first chamber and in the grooves extending therefrom and adapted to receive the conductors. The plug body parts are then located in correct relation by entering projections 46 and bosses 90 on the male body part into their respective notches 47 and sockets 91 on the female body part and the body parts are drawn together by the use of bolts 92 and nuts 93. The fuses are then severally inserted in sockets of the prongs and the prong ends are compressed to enter the lugs thereon into the grooves in the entry passageway into the plugs. Axial pressure is exerted on the prong to compress the spring until the lugs enter the second chamber whereupon the prong is given a partial turn to snap the lugs into the notches 42, at which time the prong is properly aligned for entry into an electrical receptacle. During the time the prongs are being inserted, the several chambers aid the grooves 45 and the lugs 59 in preventing misalignment of the prongs so that there can be no binding action during the prong insertion.

In use, when it is desired to inspect or replace a fuse, it is necessary only to press axially on a prong and to turn the prong in either direction to bring the lugs out of the notches 42 and into alignment with the grooves 45 whereupon the spring will force the fuse and the prong out of the plug body. The springs need have only sufficient force to secure adequate contact between the fuse contact and prong, and the usual size of prong makes an ample handle for insertion and the removal of a fuse and prong without tools and by the average person.

A modified form of plug is shown in Figs. 22 to 27, inclusive, and differs from the structure previously described in that the body parts now form a first chamber having a cylindrical portion 96, a conical portion 97 and another cylindrical portion 98. Chamber portion 96 receives a "strain-relief"-contact member (shown particularly in Figs. 25, 26 and 27) which comprises a metal disk 101 with a rim portion 102 and a central aperture 103 defined by pointed teeth 104. In manufacture the disk 101 is shaped as shown in Fig. 26 which provides a relatively large aperture 103 so that an insulated electrical conductor 105 may be readily passed therethrough. After the electrical conductor 105 extends through the aperture of the "strain-relief" member, the disk teeth 104 are pressed or struck into the plane of rim 102 which forces the points of the teeth through the conductor insulation and into the strands of the conductor itself. Hence, disk 101 provides both a permanent electrical connection with the conductor and means for transferring tension on the cord to the plug body. Disk 101 is of such size that it cannot pass out of the first cylindrical body cavity 96 and provides a seat for a spring 106 which is also a good electrical conductor. The spring is conical so that it is always retained in conical cavity 97 and cannot pass into cylindrical cavity 98 for a sufficient distance to interfere with insertion of the fuse 62 thereinto.

If desired, the tension-resisting or "strain-relief" function may be combined with a member performing a contacting function, in the form in which such combined element is shown in Figs. 28 and 29. In such figures resilient conductive material is again formed with a disk-like portion 108 having an aperture defined by pointed

teeth as above described, and with a tap or tongue 109 extending therefrom for bending on itself as shown in Fig. 29 to form a leaf spring. The body parts then need not have the conical cavity 98 and the tongue 109 performs the function of both a spring and a contact.

In the structure shown in Figs. 31 to 33, inclusive, the "strain-relief"-contact member is formed from a single resilient piece of metal with a generally disk-like portion 113 from which is struck a tongue 114 bent out of the plane of the disk and from which a lug 115 is bent at an angle to the plane of the disk. The lug 115 has an aperture defined by teeth 116 similar to the teeth previously described, to penetrate the insulation of a cord into contacting relation with the conductor in the cord. The lug 115 also has a plain circular aperture 117 of a size for ready passage therethrough of an insulated conductor. To use the "strain-relief"-contact member 113-116, the connector body parts are severally made with a pair of cavities 120 into which such member seats with slight play and the cavities are severally joined by grooves 121 with a single groove to the end of the plug body part. It is desirable that the cavities 120 be of such shape and size that the lug 115 may engage a shoulder 122 in the body part, without materially displacing contact 114 relative to the axis of the first chamber 120, 121 and 98, when the conductor is attached to the lug and is placed under tension. When the conductor is to be attached, it is first threaded through hole 117 and then bent to enter the hole defined by teeth 116 where the electrical connection is made. Hole 117 is slightly offset from groove 121 so that tension on the cord is resisted by several bends in the cord as it passes from the connection through the plain aperture and from such aperture through the groove 121 and out of the plug.

Fig. 33 shows interlocking of the body parts by a rib 125 extending peripherally about one body part and engaging in a complementary groove in the other body part. Such interlock provides for simpler molds and molding than the structures previously described but requires use of two molds as compared to only one mold when the interlock of Figs. 1 to 7 is used.

Fig. 34 illustrates a modified form of prong in which the socket halves are now formed to provide three separate tongue-like members at each end of the prong strip, the several pairs of tongues 126 and 127 coacting to form a socket for receiving the fuse 62 and a tongue 128 forming one of a pair of lugs for holding the prong and fuse in the body as previously described. The present socket construction allows shaping of the pairs of tongues 126 and 127 to form a socket of exactly the size and shape of the fuse end to grip the fuse end sufficiently firmly for movement of the fuse and prong as a single element in the insertion and removal thereof as previously described. The lug 128 is now of greater length than was obtainable heretofore and hence is slightly bowed and formed with a rounded end. The present construction accordingly takes full advantage of the resilience of the prong material to hold the fuse in the prong socket and to hold the prong firmly in the connector body while compensating for manufacturing irregularities in either the connector body or the prongs.

Figs. 35 to 40, inclusive, show a multiple outlet tap having two similar body parts generally designated 133 and 134. Such parts are of dielectric material and have coacting cavities to

provide a pair of first and second chambers for respectively receiving a contact member and fuse and for receiving the prong socket ends when the parts are assembled. The first chambers are formed by cavities 135, 136 and 137 in each connector body part. Each body part is provided with two apertures 138 and 139 leading from a first chamber and spaced to receive the prongs of a plug on an extension cord to be connected with the tap.

A resilient metallic contact member is shown in Fig. 40 and is generally designated 142. Such member provides a bar portion 143 from which strips extend and are bent on themselves to provide a pair of resilient contacts 144 and 145 adjacent the ends of the bar, and a contact 146 intermediate the end contacts. It will be noted that each of the two contact members 142 extends across the joint of the two body parts with the bar portion 143 resting on a partition 150 separating the first and second chambers when the body parts are assembled. The contact members 142 are so mounted in the first chamber as to present the bow or bend of the contacts 144, 145 toward the several apertures 138 and 139. Each of the contacts 144 and 145 is of such length that the free ends thereof severally rest on a wall of cavities 135 in line with the apertures 138 and 139 under pressure due to the form of the contacts 144 and 145, so that extension cord plug prongs are firmly gripped between the cavity wall and the contacts upon insertion of the plug prongs into the tap. Each of the contacts 146 extends into a cavity 136 and is bent on itself so that the free end of the contact extends across the cavity 137 to bear on an end of a fuse 62 in cavity 137 and with considerable pressure produced by forming the contact as a relatively long leaf spring.

The two second chambers in the assembled tap are formed by cylindrical cavities 154 with a groove 155 in each cavity wall and with a pair of notches 156 in diametric relation in a wall of each groove. The end portions of the cavity 154 adjacent the end of the body part are provided also with two grooves 157 which are also diametrically related and are preferably placed on a diameter at a right angle to the diameter through the notches 156. The grooves 157 provide for entry of the prong lugs into the second chamber where the prong is located and held in the manner previously described.

The two tap body parts 133 and 134 may be provided with either of the disclosed forms of joint surface interlock.

The prongs employed in the multiple tap are of the form shown previously in Fig. 34 and need not be again described.

The advantages resulting from the above constructions are clearly seen if the constructions are considered from the separate viewpoints of a manufacturer, insurance underwriters, and users. From the manufacturer's viewpoint the construction is especially attractive because of the small number of parts required, thus requiring a minimum of tooling and low inventory. All of the constructions are exceptionally easy to make because all of the metal parts are resilient so that no close tolerances are required. The constructions are easy to assemble because only pressure or a blow with a suitable tool, will attach the conductors to the contacts, the metal parts snap into place rather than requiring fastening in the body parts, the joint surfaces of the body parts are interlocked to avoid shifting during riveting

or placing of a screw and the fuses and prongs are inserted last so that there can be no fuse breakage or damage to the prongs.

From the viewpoint of underwriters, the structures are desirable because the parts are subjected to only a minimum of stresses during assembly, the electrical connections are not subjected to strain which is taken up either in the connector body directly or by bearing of the contact members on the body. The conductors are permanently electrically connected with the contact members and the fuses are held only resiliently and not subjected to any material mechanical stresses.

From the viewpoint of the user, it is never necessary to disassemble the structures for the purpose of tightening a contact-cord connection, the two conductive paths within the connector are completely separated at all times, the fuses are removable and replaceable without tools, and breakage of a fuse would not be dangerous and the broken fuse fragments can be easily removed.

Because of the fact that the present invention is applicable both to plugs attached to electrical cords and to multiple outlet electrical taps, the word "connector" is used as a term generic to both the above articles.

I claim:

1. In a connector for attaching electrical conductors to an electrical receptacle and for removably receiving the individual fuses for the conductors, a plurality of electrical insulating body parts adapted to be joined for coacting in defining a plurality of chambers therein and severally open from one end of the body for severally receiving the fuses, and prongs severally insertable into the body for several electrical connection thereof with the fuses and removable from the body through the open ends of the chambers after the body parts are joined, the prongs being adapted to enter the electrical receptacle.

2. In a connector for attaching electrical conductors to an electrical receptacle and for removably receiving the individual fuses for the conductors, a plurality of electrical insulating body parts adapted to be joined for coacting in defining a pair of axially aligned and joined first and

50 second chambers, the second chambers being

open at one end thereof for severally receiving

the fuses, and prongs severally insertable into the

second chamber for several electrical connection

with the fuses, the prongs and fuses being man-

ually insertable and removable from the body

after the body parts are joined.

3. In a connector for attaching electrical conductors to an electrical receptacle and for removably receiving the individual fuses for the conductors, a plurality of electrical insulating body parts adapted to be joined for coacting in defin-

60 ing a plurality of chambers therein and open

from one end of the body for severally receiving

the fuses, and resilient metallic prongs compres-

65 sible for insertion through the open ends of and

expansible into engagement with the chambers

in several conductive relation with the fuses, the

prongs and the fuses being severally removable

from and replaceable in the body in the assem-

70 bled relation of the body and as a unit.

4. In a connector for attaching electrical conductors to an electrical receptacle and for removably receiving the individual fuses for the conductors, a plurality of electrical insulating body

75 parts adapted to be joined for coaction in defin-

ing a plurality of aligned and joined chambers therein and open from one end of the body for severally receiving the fuses, and prongs insertable into the body for several electrical connection with the fuses and removable from the body through the open ends of the chambers after the body parts are joined, the prongs having sockets at one end for severally receiving an end of a fuse and being manually engageable in the chambers for retaining the fuses in the body.

5. In a connector for attaching electrical conductors to an electrical receptacle and for removably receiving the individual fuses for the conductors, a plurality of electrical insulating body parts adapted to be joined for coaction in defining a pair of axially aligned first and second chambers, the pairs of chambers being severally open at one end thereof for severally receiving the fuses, the second chambers severally having a groove in the wall thereof and notches in a side wall of the groove, and prongs manually insertable into the body for the several electrical connection with the fuses and removable from the body after the body parts are joined for inserting and removing the fuses, the prongs severally having lugs extending laterally therefrom for entry into the second chamber grooves and engagement in the notches therein.

6. In a connector for attaching electrical conductors to an electrical receptacle and for removably receiving the individual fuses for the conductors, a plurality of electrical insulating body parts adapted to be joined for coaction in defining a plurality of first and second chambers open from one end of the body for severally receiving the fuses, the second chambers severally having a groove in the wall thereof and notches in a side wall of the groove, and resilient prongs having a resilient socket at one end thereof for receiving an end of a fuse, the prongs severally having resilient lugs extending from the sides of the sockets for entry into the second chamber grooves for engagement in the notches thereof.

7. In a connector for attaching electrical conductors to an electrical receptacle and for removably receiving the individual fuses for the conductors, a plurality of electrical insulating body parts adapted to be joined for coaction in defining a plurality of chambers open from one end of the body for severally receiving the fuses, resilient means severally connectible with the conductors and severally retained in one of the body chambers for individually urging the fuses out of the chambers through the open end thereof, and prongs severally insertable into the chambers for retaining the fuses therein in electrical connection with the resilient means, and a fuse and prong body insertable into and removable from the body as a unit through their respective chamber open ends after the body parts are joined.

8. In a connector for attaching electrical conductors to an electrical receptacle and for removably receiving the individual fuses for the conductors, a plurality of electrical insulating body parts adapted to be joined for jointly defining a plurality of chambers open from one end of the body for severally receiving the fuses, contacts each having a portion formed as a leaf spring, the contacts being severally connectible with the conductors and severally retained in a body chamber, the leaf spring portions of the contacts individually acting on the fuses for urging the fuses toward the open end of the chambers, and prongs insertable into the body for retaining the

fuses therein and insertable into and removable from the body after the body parts are joined.

9. In a connector for attaching electrical conductors to an electrical receptacle and for removably receiving the individual fuses for the conductors, a plurality of electrical insulating body parts adapted to be joined for jointly defining a plurality of chambers therein for severally receiving the fuses, the chambers severally having an end open at one end of the connector, contacts severally connected with the conductors and severally retained in a body chamber for engagement severally with the fuses, the conductors being severally mechanically engaged with the contacts in addition to the electrical connection therewith to press the contacts severally against a body surface upon tensioning of the conductors, and prongs severally insertable into the chambers for retaining the fuses therein and removable therefrom after the body parts are joined, the fuses and prongs being severally insertable as a unit through the open chamber ends at that end of the body in contact with the receptacle when the connector is in use.

10. In a connector for attaching electrical conductors to an electrical receptacle and for removably receiving the individual fuses for the conductors, a plurality of electrical insulating body parts adapted to be joined for jointly defining a plurality of aligned and joined first and second chambers, the second chambers being open from one end of the body for severally receiving the fuses, the second chambers severally having a groove in the wall thereof and notches in a side wall of the groove, contacts severally having portions forming a spring and being severally connected with the conductors and severally retained in a chamber, the spring portion of the contacts acting on the fuse for urging the fuse toward the open end of the chamber, and resilient prongs having a socket at one end thereof for receiving an end of a fuse and for insertion and removal of a prong and a fuse as a unit, the prongs severally having resilient lugs extending from the sides of the sockets for entry into the second chamber grooves for rotation therein into and out of engagement in the notches thereof whereby the prongs are positioned for entry into the receptacle.

11. In a connector for attaching electrical conductors to an electrical receptacle and for removably receiving the individual fuses for the conductors, a plurality of electrical insulating body parts adapted to be joined for coaction in defining a plurality of chambers therein, the chambers being open at one end of the connector for severally receiving the fuses, projections formed on one of the body parts for entry into a socket in the other body part for gripping the conductors to resist tension thereon, and prongs insertable into the body for several electrical connection with the fuses and removable from the body after the body parts are joined, the prongs being adapted to enter the electrical receptacle.

12. In a connector for attaching insulated electrical conductors to an electrical receptacle and for removably receiving the individual fuses for the conductors, a plurality of electrical insulating body parts adapted to be joined for coaction in defining a plurality of open-ended chambers for severally receiving the fuses, the chambers being connected with a groove having projections from the wall thereof for embedment in the insulation of the electrical conductors to resist

movement of the conductors relative to the body upon tensioning of the conductors, and prongs insertable into the chambers for several electrical connection with the fuses and removable therefrom after the body parts are joined, the prongs being adapted to enter the electrical receptacle.

13. In a connector for attaching electrical conductors to an electrical receptacle and for removably receiving the individual fuses for the conductors, a plurality of electrical insulating body parts adapted to be joined for jointly defining a plurality of open-ended chambers for severally receiving the fuses, the chambers being connected by a groove having staggered projections from the walls thereof for holding the conductors separately in sinuous relation in the groove to

resist tension on the conductors, and prongs severally insertable into the chambers for the several electrical connection with the fuses and removable from the body when the body parts are joined.

MATTHEW E. GERLAT.
